CLAIM

The ornamental design for a roadway lamp fixture, as shown and described.

DESCRIPTION

FIG. 1 is a front perspective view of a roadway lamp fixture showing our new design;

FIG. 2 is a top plan view thereof;

FIG. 3 is a bottom plan view thereof;

FIG. 4 is a right side elevational view thereof, the left side elevational view being a mirror image thereof;

FIG. 5 is a front elevational view thereof; and,

FIG. 6 is a rear elevational view thereof.

The broken lines in the Figures show portions of the roadway lamp fixture which form no part of the claimed design. The shade lines in the Figures show contour and not surface ornamentation.
